UNITED STATES PATENT OFFICE.

GEORGE S. WEINERTH, OF READING, PENNSYLVANIA.

REINFORCING MECHANISM FOR CIRCULAR-KNITTING MACHINES.

1,351,883.

Specification of Letters Patent. Patented Sept. 7, 1920.

Application filed July 16, 1919. Serial No. 311,155.

To all whom it may concern:

Be it known that I, GEORGE S. WEINERTH, a citizen of the United States, residing at Reading, in the county of Berks and State of Pennsylvania, have invented certain new and useful Improvements in Reinforcing Mechanism for Circular-Knitting Machines, of which the following is a specification.

My invention relates particularly to circular knitting machine in which approximately half of the needles are operated at intervals for narrowing and widening and also to knit a reinforcing thread into the fabric, as commonly required for hosiery. The invention provides for accurately dividing the needles and for utilizing determined additional ones to knit-in the reinforcing thread during circular knitting, as fully described in connection with the accompanying drawing, and the novel features are clearly defined in the claims.

Figure 1 is a plan view showing part of a cam ring mechanism embodying my invention.

Fig. 2 is a cross-sectional view on the line 2—2 of Fig. 1.

Fig. 3 is a view showing three needles with differently formed butts as employed in my invention.

Fig. 4 is a diagrammatic view indicating the knitting cams in normal position with the relative positioning of the several groups of needles in passing.

Fig. 5 is a diagrammatic view similar to Fig. 4, but with the stitch cams omitted to indicate their withdrawal from action and the pivoted leveling cam shown in leveling position.

The drawing indicates only so much of well known knitting machine construction as is required for fully setting forth the present invention.

The cam ring 5, as shown, is of the fixed type carrying knitting cams operative upon needles mounted in a rotative cylinder; these cams including stitch cams 6, 6 which are movable into and out of the path of the needles in well known manner, as indicated, while the needle lowering top center cam 8 and the leveling lower center cam 9 are secured in said path by means of a plate 10 fixed to the cam ring. Ordinary means for carrying a reinforcing thread, to be employed as desired in connection with the main knitting thread, are indicated by the pivoted thread-carrier finger 11.

In my improved construction I employ the usual half circle series of short-butt needles, such as, shown at 15 Fig. 3, in connection with a series of long-butt needles 60 certain of which differ from the usual form indicated at 16, by having the end portions of their laterally extending butts reduced in height, as indicated in needle 17. This change in the form of the butts adapts 65 these needles 17 to serve as ordinary long butts in the usual raising of the needles into action, but permits them to be kept in action with the short butt needles when desired as hereinafter described.

As indicated in Fig. 4 a small group of these special needles 17 is located adjacent the short-butt series, at each end of the latter, so as to operate with the short-butt needles in knitting-in the reinforcing thread 75 fed thereto from the carrier-finger 11; the particular purpose being to determinedly widen the so-called high-splice which is ordinarily knitted above the heel of a stocking, and also the reinforced bottom of the 80 circularly knitted portion of the foot if desired.

To provide for operating the needles so as to effect this purpose, I form the top center cam 8 with two butt-engaging portions, 8^a 85 and 8^b, arranged at different levels; the lower-extending portion 8^a thereof being set back so as to be cleared entirely by the passing short-butt needles 15, and being also cleared by the normally-wide butt portions 90 of the reduced-butt needles 17 so as to cause the latter to pass the taking point of the reinforcing thread with the short-butt needles 15, while the normal long-butt needles 16 are lowered by said portion 8^a before they 95 reach the yarn-taking point. The reduced butt ends of the needles 17 may slightly engage the lowermost point of the cam 8 without lowering said needles sufficiently to prevent them from taking the reinforcing 100 thread with the short-butt needles 15, but serve the full purpose of the normal long butts so far as the raising of the long butt needles out of action is concerned; which raising is effected by the usual dividing cam, not shown, preliminary to the narrowing-and-widening operations.

In the construction shown the stitch cams 6, 6 are withdrawable from the path of the needles, while the center cams are not; so that the downwardly extended butt-engaging portion 8^a of the top cam 8 will depress the nor-

mal long-butt needles 16 below the level of the short butt needles 15, not only during the knitting operation, as desired in the improved operation above described, but also when the 5 stitch cams are withdrawn. To provide for leveling all the needles, as is required in knitting half hose, I therefore employ a movable lower center cam 9 which is adapted to permit the required lowering of the long- 10 butt needles 16 when it is in normal position as indicated in Fig. 4, but which is swung upward on its pivot 27 as indicated in Fig. 5, when it is desired to level all the needles. This upward movement of the 15 cam 9 is effected by means of a post or plate 28 on the usual stitch cam bracket 29 which engages a conically headed pin 30 on the free end of the cam, as shown, and when thus positioned by the withdrawn stitch cam 20 bracket it will lift all the long-butt needles to the level of the short-butt needles; the needle cylinder being stopped with the latter only in center cam position. In machines where the center cams are withdrawn with 25 the stitch cams for leveling purpose, no special device is required.

With my improved construction I provide in a simple and effective manner for positively and accurately locating the reinforcing splicing yarn on determined needles only, and also provide for extending the same beyond the usual short-butt needles to desirably increase the width of the circularly knitted reinforced fabric without affecting the usual division for properly knitting the heel and toe portions.

What I claim is:—

1. In a circular knitting machine, the com-

bination with reinforcing thread mechanism, of series of long butt and short butt needles 40 certain of the former having reduced-end butts, and means for operatively positioning said reduced-end long butt needles either with the short butt needles or with the other long-butt needles to vary the extent of the 45 reinforced knitting.

2. In a circular knitting machine, the combination with reinforcing thread mechanism, of series of long butt and short butt needles 50 certain of the former having reduced-end butts, a needle-lowering center cam having engaging portions at different levels for the long butts and short butts respectively, with- 55 drawble stitch cams, and a pivotally movable leveling cam below said center cam.

3. In a circular knitting machine, the combination with reinforcing thread mechanism, of series of long butt and short butt needles 60 certain of the former having reduced-end butts, a needle-lowering center cam having engaging portions at different levels for the long butts and short butts respectively, and a pivotally movable leveling cam below said center cam.

4. In a circular knitting machine, the combination with reinforcing thread mechanism, of series of long butt and short butt needles 65 certain of the former having reduced-end butts; stitch cams jointly movable out of the needle path; a needle-lower- 70 ing center cam having engaging portions at different levels for long butts and short butts respectively; and a pivotally movable leveling cam below said center cam.

In testimony whereof I affix my signature. 75
GEORGE S. WEINERTH.
